(57) **CLAIM**

We claim the ornamental design for a luggage, as shown and described.

DESCRIPTION

FIG. 1 is a perspective view from the front and to one side of a first embodiment of a luggage;

FIG. 2 is a perspective view from the back and to the other side of the luggage of FIG. 1;

FIG. 3 is a side elevation view of one side of the luggage of FIG. 1;

FIG. 4 is a back elevation view of the luggage of FIG. 1;

FIG. 5 is a side elevation view of the other side of the luggage of FIG. 1;

FIG. 6 is a front elevation view of the luggage of FIG. 1;

FIG. 7 is a perspective view from the front and to one side of a second embodiment of a luggage;

FIG. 8 is a perspective view from the back and to the other side of the luggage of FIG. 7;

FIG. 9 is a side elevation view of one side of the luggage of FIG. 7;

FIG. 10 is a back elevation view of the luggage of FIG. 7;

FIG. 11 is a side elevation view of the other side of the luggage of FIG. 7; and,

FIG. 12 is a front elevation view of the luggage of FIG. 7. The design extends the entire indefinite length as shown in the drawings.

The dash-dot-dash broken line in FIGS. 1–6 illustrates surface indicia which forms no part of the claimed design. The dash-dot type broken line illustrates portions of the luggage which form no part of the claimed design.

1 Claim, 6 Drawing Sheets
